G. D. JONES

DUSTPROOF DOOR FOR WARDROBE TRUNKS

Filed May 2, 1923

UNITED STATES PATENT OFFICE.

GEORGE D. JONES, OF PETERSBURG, VIRGINIA.

DUSTPROOF DOOR FOR WARDROBE TRUNKS.

Application filed May 2, 1923. Serial No. 636,149.

The present invention relates to wardrobe trunks of the type embodying drawer and clothes sections, the latter having its front and upper portion open and a hinged top 5 closing the upper end of the clothes section.

The invention has for its main object to close the front of the clothes section in a manner to exclude dust and at the same time retain the articles of clothing supported 10 upon hangers within the section and covering the same when the trunk is open so as to hide them from view.

A further object of the invention is the provision of a door which is light and strong 15 and capable of being easily placed in position and readily removed as required.

Other objects and advantages will be apparent and suggest themselves as the nature of the invention is understood.

20 While the drawings illustrate an embodiment of the invention it is to be understood that in adapting the same to meet different conditions and requirements, various changes in the form, proportion and minor 25 details of construction may be resorted to without departing from the nature of the invention.

Referring to the accompanying drawings forming a part of the application:

30 Figure 1 is a perspective view of a wardrobe trunk embodying the invention, the same being open, the dotted lines indicating the drawer section and the full lines the clothes section and the hinged top thereof,

35 Figure 2 is a vertical transverse sectional view of the clothes section with the hinged top in closed position,

Figure 3 is a sectional view on the line 3—3 of Figure 2, parts being broken away,

40 Figure 4 is a top plan view of a portion of the clothes section, showing more clearly the door and the retaining means therefor,

Figure 5 is a fragmentary sectional view on the line 5—5 of Figure 3, looking in the 45 direction of the arrows, and

Figure 6 is a detail perspective view of a corner portion of the door showing the parts on a larger scale.

Corresponding and like parts are referred 50 to in the following description and designated in the several views of the drawings by like reference characters.

The wardrobe trunk illustrated comprises a drawer section 1, a clothes section 2 which 55 is open at the front and upper end, and a hinged top 3 for closing the upper end of

the section 2. The clothes section 2 comprises a back 4 and sides 5. A substantial metal frame 6 of approximately U-form is riveted or otherwise secured to the upper 60 portion of the back and sides of the section 2 and reinforces and strengthens the same. Transverse rods 7 are supported by the frame 6 adjacent the upper ends of the sides 5 and are designed to receive the hangers, 65 not shown, which support the articles of clothing when in position within the section 2. Strips 8 are attached to the inner sides of the vertical edge portions of the side walls 5 and constitute stops to prevent outward displacement of the door. Cleats 9 are attached to the inner faces of the sides 5 some distance from the upper ends thereof and are spaced from the strips 8 a distance to receive the door and prevent inward displacement thereof. Inward displacement of 70 the upper portion of the door is prevented by the rods 7 and the inturned ends of the reinforcing and bracing frame 6.

A shoe box 10, removably fitted within the 80 lower portion of the section 2, partly closes the front thereof. The door 11 may be of any substantial and light structure and is adapted to close the front of the section 2 above the shoe box 10 and when in position 85 rests upon the latter and is retained in place by means of the top 3 when the latter is closed. The door 11 is slideable and operates in the guides formed between the strips 8 upon one side and the cleats 9 and rods 7 90 upon the opposite side. The door comprises a substantial frame and light panels 12 of textile and the corners are reinforced by metal stripings 13. The door is removable by a sliding movement upwardly through 95 the upper end of the section 2 and is similarly placed in position by a sliding movement. When the door is in place, the front of the section 2 is closed, thereby excluding dust and at the same time protecting the 100 clothing and concealing the same from view.

What is claimed is:

1. A wardrobe trunk embodying a clothes-hanger section having a hinged lid adapted to open upwardly and an open front, the inner faces of the side-walls of said section being provided with vertical guideways, a receptacle in the bottom of the trunk in line with said guideways, a door slideable vertically in said guideways and adapted to close 105 the entire front of the section above said receptacle and to open the same when removed,

said door being adapted to be removed entirely from said section by sliding it vertically out of said guideways and being of such length that it will be held in position down against the receptacle when said hinged lid is closed down.

2. A wardrobe trunk embodying a drawer section and a clothes-hanger section having a hinged lid, adapted to open upwardly, and an open front, the inner faces of the side walls of said clothes-hanger section being provided with vertical guideways, a receptacle in the bottom of the trunk in line with said guideways and entirely closing the lower part of the hanger section, a door slidable

vertically in said guideways and adapted to close the entire front of the clothes-hanger section above said receptacle and to open the same when removed, said door being adapted to be removed entirely from said clothes-hanger section by sliding it vertically out of said guideways and being of such length that it will be held in position down in engagement with the receptacle when said hinged lid is closed down and thus serve to hold the receptacle in place while the lid is closed. 20

In testimony whereof I affix my signature.

GEORGE D. JONES.
